US00D952082S

(12) **United States Design Patent** (10) **Patent No.:** **US D952,082 S**
(45) **Date of Patent:** **** May 17, 2022**

(54) **GOLF CLUB HEAD**

(71) Applicant: **PARSONS XTREME GOLF, LLC**,
Scottsdale, AZ (US)

(72) Inventors: **Matthew T. Andrews**, Scottsdale, AZ
(US); **Caleb S. Kroloff**, Phoenix, AZ
(US); **Robert R. Parsons**, Scottsdale,
AZ (US)

(73) Assignee: **PARSONS XTREME GOLF, LLC**,
Scottsdale, AZ (US)

(**) Term: **15 Years**

(21) Appl. No.: **29/782,219**

(22) Filed: **May 5, 2021**

Related U.S. Application Data

(63) Continuation-in-part of application No. 29/782,089,
filed on May 4, 2021, now Pat. No. Des. 940,804.

(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view golf club head of FIG. 1;
FIG. 7 is a left side view of the golf club head of FIG. 1;
FIG. 8 is a right side view of the golf club head of FIG. 1;
FIG. 9 is a top perspective view of a second embodiment of a golf club head;
FIG. 10 is a bottom perspective view of the golf club head of FIG. 9;
FIG. 11 is a front elevational view of the golf club head of FIG. 9;
FIG. 12 is a rear elevational view of the golf club head of FIG. 9;
FIG. 13 is a top view of the golf club head of FIG. 9;
FIG. 14 is a bottom view golf club head of FIG. 9;
FIG. 15 is a left side view of the golf club head of FIG. 9; and,
FIG. 16 is a right side view of the golf club head of FIG. 9.
The broken lines shown on the drawings form no part of the claimed design.

1 Claim, 8 Drawing Sheets
